UNITED STATES PATENT OFFICE.

SIDNEY C. CHAMBERS, OF DURHAM, NORTH CAROLINA.

MOTHPROOF CLOTHES-WRAPPER.

1,100,121.

Specification of Letters Patent. Patented June 16, 1914.

Application filed December 26, 1913. Serial No. 808,851.

To all whom it may concern:

Be it known that I, SIDNEY C. CHAMBERS, a citizen of the United States, residing at Durham, in the county of Durham and State 5 of North Carolina, have invented a new and useful Mothproof Clothes-Wrapper, of which the following is a specification.

The present invention appertains to clothes wrappers or envelopments and aims 10 primarily to provide a novel or improved moth or insect proof device of that character.

It is the object of the present invention to provide a moth proof clothes or garment 15 wrapper of unique construction, in order to adapt it for suspension within a clothes closet or wardrobe, and in order that the wrapper may be placed within a trunk, chest or other container, to serve as a moth 20 proof lining therefor.

Another object of the present invention is to provide a clothes or garment wrapper of the nature indicated, embodying novel closure means therefor, whereby the wrapper 25 may be tightly sealed when the wrapper is closed.

With the foregoing general objects outlined, and with other objects in view, which will appear as the description proceeds, the 30 invention resides in the combination and arrangement of parts and in the details of construction hereinafter described and claimed, it being understood that changes in the precise embodiment of the invention herein 35 disclosed can be made within the scope of what is claimed without departing from the spirit of the invention.

The invention has been illustrated in its preferred embodiment in the accompanying 40 drawings, wherein—

Figure 1 is an inside view of the wrapper in open condition, portions being broken away. Fig. 2 is an outside view of the wrapper in open condition. Fig. 3 is a sectional 45 detail of the wrapper, illustrating the same as applied to a clothes hook. Fig. 4 is an enlarged cross sectional view of the wrapper in closed condition, portions being broken away.

The wrapper or envelopment embodies a textile or fabric blank including the sections or halves 1 and 2 adapted to be folded together upon their median line. The sections or leaves 1 and 2 are of rectangular

contour, the blank, as a whole, being approximately square, although it may be of various proportions.

The wrapper or envelopment is of flexible three ply structure, including a facing 3 of canvas or other suitable material of such texture as to withstand the external conditions, a lining 4 of silk, cotton or other material of such texture as to suit the clothes or garments, and a moth or insect repelling filling or sheet 5 interposed or sandwiched between the facing and lining. This moth or insect repelling sheet or ply 5, is preferably in the nature of a sheet of paper or the like, coated with tobacco, in either leaf, granulated or dust form, although cedar dust or shavings, or other suitable composition, may be substituted for the tobacco. The three plies are co-extensive throughout the area of the wrapper or envelopment, and are stitched or sewed together throughout their area by numerous lines of longitudinal and cross stitches, as indicated in the drawing. In this manner, the moth repelling 75 sheet is confined between the facing and lining, and will render the wrapper or envelopment moth or insect proof.

The section or half 1 of the wrapper or envelop constitutes the body or back of the wrapper, having the section or closure flap 2 at one side and adapted to be folded thereover.

In order to permit the clothes or garments to be hung or suspended within the wrapper, and in order to permit the wrapper to be suspended or hung from a clothes hook, nail or the like, a looped strap 6 and the second looped strap 7 are secured internally and externally to the upper end of the body or back 1, by means of rivets or other securing means 8, the loop 6 hanging or depending 90 downwardly upon the inner side of the back, and the loop 7 projecting upwardly upon the outer side of the back. A ring 9 is preferably engaged by the outer loop 7, to engage a clothes hanger 10, a nail, or other 100 member, from which the wrapper is to be suspended. A clothes hanger 11, or a number of clothes hangers or other articles may be suspended from the inner loop 6, it being noted that the loops 6 and 7 being connected by the rivets 8, will permit the hanger 11 to be suspended directly from the clothes hook 10, or the like, without subjecting the

wrapper to any strain whatever due to the weight of the garment or garments suspended from the loop 6.

As a means for sealing the wrapper, when the closure flap 2 is swung over the back 1, metallic strips 12 are applied exteriorly to the end portions of each of the sections of the wrapper, and similar strips 13 are applied exteriorly to the free edge 18 of the said sections, a pair of strips 13 being provided for each portion, while a single strip 12 is provided for each end of each section. The strips 12 and 13 are pivoted together at the corners of the wrapper, as at 14, and the adjoining ends of the side strips 13 are pivoted together as at 15. Thus, the strips as a whole provide a frame for the wrapper, to lend rigidity to the wrapper, so as to hold the wrapper in proper condition when in use. Attention is also directed to the fact that the break joints between the side links 13, permit the inner or adjoining ends of the side links 13 to be moved inwardly or toward each other, whereby the end strips 12 may be moved toward each other in parallelism, until all of the strips are brought together within a small compass, with the wrapper proper in order that the entire device may be folded with a small compass, to be readily stored, shipped or carried.

Packing strips 16, of leather, or other suitable material, are disposed interiorly along the edge and end portions of the back 1 and closure flap 2 of the wrapper, to complement the metallic strips 12 and 13. The packing strips 16 of the wrapper sections, or body and closure flap, respectively, are arranged to swing against each other, when the closure flap is swung over the back or body 1, to thereby effectively close the wrapper.

The end and side or edge strips 12 and 13 of the body or back 1 are provided with clasp or fastener elements 17 engaging through the respective strips 16, and having the heads or knobs 18 upon the inner side or face of the back, while the clasp or fastener elements 19 are attached to the end and side or edge strips 12-13 of the closure flap 2, and have snap or spring sockets 20 engaging through the respective packing strips 16 whereby when the closure flap is swung over the back the spring sockets 20 may be snapped over the heads or knobs 18 of the clasp or fastener elements 17 in the manner of the ordinary glove fasteners. This permits the ends and free or side edge of the closure flap to be effectively attached to the ends and free edge of the back or body 1 to hold the packing strips 16 in tight engagement, for closing the wrapper.

It is preferable to render the frame strips 12 and 13 removable, in order that the wrapper proper may be employed without

the frame. Thus, when the frame strips are removed, the wrapper could be applied to a trunk, chest or other container, for providing a moth or insect proof lining therefor, as will be apparent without illustration or further description thereof.

In use, the present wrapper may be employed in a wardrobe, clothes closet, or the like, the ring 9 being readily engaged to the clothes hook, or other supporting element, for supporting the back of the wrapper, as suggested in Fig. 3. Then, when the closure flap 2 is opened, the clothes or garments may be readily suspended from the inner loop 6, whereby the closure flap may be closed over the clothes or garments to inclose or envelop the same. As above intimated, the closure flap may be fastened to the back or body, by engaging the clasp elements 19 to the clasp elements 17 of the back or body. The wrapper being thus closed, will prevent the entry of moths or other insects thereinto, and the structure of the wrapper proper will effectively preclude moths or other insects from attacking the clothes or garments.

When the wrapper is not in use, the same may be compactly folded or collapsed, either when in open or closed condition, the side or edge strips 13 being readily doubled or folded together, so as to permit the strips 12 to fold together also. When the strips or frame members are thus folded together, with the wrapper blank, the entire structure may be readily stored, shipped or carried about.

Having thus described the invention, what is claimed as new is:—

1. A flexible clothes wrapper embodying two outer cloth plies forming a facing and lining, and an intermediate paper ply coated with an insect-repelling substance, the three plies being stitched together throughout their area.

2. A clothes wrapper embodying a fabric body having a closure flap to fold thereover, loosely-connected foldable metallic strips applied to the end and edge portions of the body and flap, and interengageable clasp elements carried by the strips of the body and flap, respectively.

3. A clothes wrapper embodying a fabric back having a closure flap arranged to fold thereover, metallic strips applied to the end and edge portions of the back and flap, the strips of the back and flap, respectively, being pivoted together, and opposite strips being foldable to bring the others together, and interengageable clasp elements carried by the strips of the back and flap, respectively.

4. In a clothes wrapper, a rectangular fabric back having a rectangular closure flap arranged to fold thereover, a metallic strip applied to each end of the back and

flap, a plurality of metallic strips applied to the free edge of the back and flap, the adjoining ends of the last mentioned strips being pivoted together, and the remote ends 5 of the last mentioned strips being pivoted to the first mentioned strips, and interengageable clasp elements carried by the strips of the back and flap respectively.

5. In a clothes wrapper, a fabric back 10 having a closure flap arranged to fold thereover, metallic strips applied exteriorly to the end and edge portions of the back and flap, packing strips applied interiorly to the end and edge portions of the back and 15 flap and complementing the aforesaid strips, and clasp elements carried by the metallic strips and engaging through the packing strips, the clasp elements of the back and flap being interengageable.

6. In a clothes wrapper, a fabric back 20 having a closure flap, pivotally connected metallic strips applied exteriorly to the end and edge portions of the back and flap, respectively, packing strips applied interiorly to the end and edge portions of the back 25 and flap and complementing the aforesaid strips, and clasp elements carried by the metallic strips and engaging through the packing strips, the clasp elements of the back and flap being interengageable. 30

In testimony that I claim the foregoing as my own, I have hereto affixed my signature in the presence of two witnesses.

SIDNEY C. CHAMBERS.
